LUMINOUS TUBE MOUNTING

Willis O. Prouty, Hermosa Beach, Calif., assignor
to Metlox Corporation, Ltd., Manhattan Beach,
Calif., a corporation of California

Application November 13, 1928, Serial No. 319,145

4 Claims. (Cl. 173—259)

This invention relates to luminous tubes, such as are now commonly used in connection with illuminated signs or display apparatus; and particularly to the means for supporting these tubes in a sign structure. Such tubes utilize rarefied gases, such as neon or helium energized by the passage of an electric current.

Such tubes, as is well known, operate on extremely high potential differences; of the order of 10 thousands of volts. Therefore the problem of leading in the connections to the tube electrodes and of properly insulating these connections is of considerable importance. It is one of the objects of my invention to make it possible effectively to 15 lead in the connections, as well as to insulate and support the tube at its ends in the structure.

In my prior Patent #1,671,741, issued May 29, 1928, there is described a sign utilizing such luminous tubes in connection with letters or characters made from comparatively heavy ceramic material, the tube being supported above the character and outlining it. The ends of the tube, where the lead-in electrodes are located, extend through the letter for making it possible to connect these electrodes to a source of potential. It is another object of my invention to improve in general the support for these ends in the character; and especially to prevent any breakdown in insulation, and also to provide a yielding grip 25 for the tube so that it can be tightly held even in the event that there are slight irregularities in the tube diameter.

It is another object of my invention to provide a simple and effective support for the tube above the character, and especially so that it can readily be arranged to compensate for irregularities in the height of the ceramic letter or character.

My invention possesses many other advantages, and has other objects which may be made more easily apparent from a consideration of several embodiments of my invention. For this purpose I have shown a few forms in the drawings accompanying and forming part of the present specification. I shall now proceed to describe these forms in detail, which illustrate the general principles of my invention; but it is to be understood that this detailed description is not to be taken in a limiting sense, since the scope of my invention is best defined by the appended claims.

50 Referring to the drawings:

Figure 1 is a plan view of a ceramic character equipped with a luminous tube and embodying my invention;

55 Fig. 2 is a longitudinal section, on a larger scale,

through that portion of the character into which the end of the tube projects;

Figs. 3, 4, 5 and 7 are similar views of modified structures; and

Fig. 6 is a detail of a tube clip for use in a 60 device embodying my invention.

In Fig. 1, I show a character 11 that can be made from such material as clay or porcelain, glazed on its upper surface. Above it is supported in any appropriate manner, a luminous tube 12 65 outlining the character, and having inwardly extending ends 13, 14. In most cases, a continuous tube length can be used to outline more than one letter or character; and in that case, the ends 13, 14 will be located on different characters. However, the mode of supporting these ends in the ceramic characters can be the same in either case.

In the form shown in Fig. 2, the inwardly turned end 14 extends into the character 11 by way of a clearance aperture 15. At its extremity it is shown as provided with an external electrode 16, of substantially the same diameter as the tube 12; however, my invention can as well be utilized in connection with tubes having internal electrodes.

80 An insulator sleeve 17, made for example from porcelain, loosely surrounds the end 14, and extends for a considerable distance beyond the end of the tube, and toward the rear face of character 11. In this way, good insulation of the tube end is secured. This sleeve is held in place in a deep recess 18 in the back of character 11, which recess connects with clearance aperture 15. It can be keyed or otherwise appropriately held against removal. In the form shown, I support the sleeve resiliently by the aid of a resilient ring 19, made from rubber or the like, tightly encompassing the sleeve 17. This ring fits into an annular groove 20 in the periphery of sleeve 17, and forms a resilient or flexible annular projection on the sleeve. A corresponding groove can be formed in the internal annular surface of recess 18, into which this projecting portion can be urged by axial movement of sleeve 17. However, to facilitate such assembly, I prefer to provide internal threads 21 in the recess 18, whereby a turning movement of sleeve 17 will serve to advance the ring 19 in the threads, into which it is intended to fit rather tightly.

100 The extension 14 of luminous tube 12 is arranged to be spaced from the inner surface of sleeve 17; for this purpose I use a gasket washer 22, which in this form is made of rubber or the like, that is tightly held between the end of 110

sleeve 17 and the bottom surface of recess 18. I purposely make the inside diameter of washer 22 slightly smaller than the diameter of tube 14 so that it tightly grips this tube and holds it 5 centered in sleeve 17.

The insulated conductor or connector 23 for leading current to electrode 16 can be provided with a spring clip 24 that clasps the electrode and makes connection therewith. A snap spring 25 10 can be supported near the end of the conductor, having projections 26 arranged to snap into an internal groove 27 in sleeve 17, and thereby hold the conductor against accidental removal from the electrode 16.

15 It is evident that the structure as disclosed effectively prevents dirt or foreign material from entering into sleeve 17 from the front of the character 11, since gasket 22 effectively closes the annular space between the tube 12 and the sleeve 20 17. Furthermore, this is all accomplished in spite of irregularities in tube diameters. The tube itself is resiliently supported and is thus free from the danger of breakage. Lastly, it is apparent that a long "creepage surface" is provided against 25 insulation breakdown; clear from inside of sleeve 17, over its lower edge, and out on the outside thereof.

In order to complete the disclosure, I indicate 30 one way in which the character 11 can be mounted on a support, such as a sheet metal backing 28. There are a plurality of round, tapered recesses 29 in the reverse face of character 11, into which is placed the head of a fastening device, such as a screw 30. Soft metal 31, such as lead or Babbitt 35 metal, can then be molded around the screw 30 to fill up the recess and to fasten this screw in place. A felt or rubber washer 32 can be interposed between the character 11 and support 28. Screw 30 can pass through the support 28 and 40 40 can be tightened as by a lock washer 33 and nut 34. Sleeve 17 passes through a clearance aperture 37 in the support 28.

In the modification shown in Fig. 3, the recess 35 that accommodates the end of sleeve 17 is provided merely with a continuous groove 36, into which the ring 19 slips, to key the sleeve 17 against 45 accidental removal. The location of this groove is such that when the locking is effected, the gasket washer 22 will be firmly held as before, between the end of sleeve 17 and the bottom of recess 35.

In the form shown in Fig. 4, the sleeve 38, that is the equivalent of sleeve 17 in the other figures, has an enlarged head 39 that fits into 55 a large recess 40 in the front side of the character 11. It is held in place resiliently by a resilient washer 41 keyed into an external groove in the sleeve, and clamped between the support 28 and the reverse side of character 11. The 60 extension 14 is resiliently gripped by a gasket washer 42 sprung into place in an internal groove 43 near the upper end of tube 14.

In the form shown in Figs. 5 and 7, the ceramic character 11 is provided as before, with a 65 clearance aperture 44 communicating with a larger diameter recess 45. In this instance, sleeve 46, the equivalent of sleeve 17, is cemented, as by hydraulic cement, into this recess, the cement being indicated at 48. A ring 47 is positioned in recess 45 and is held in place between the shoulder formed around aperture 44 and the top of sleeve 46. This ring can be made from ceramic material. The tube extension 14 passes through a clearance hole in the ring 47. A tube 70 75 54 disposed around extension 14 can be used to

center it in the ring 47. This tube can be made from hard or soft rubber, and wedged in the annular space between the ring 47 and tube extension 14.

This structure is advantageous for reasons now 80 to be pointed out. If tube extension 14 should be not very accurately bent to place it exactly in the center of aperture 44, the ring 47, having a considerable clearance in recess 45, can nevertheless be adjusted therein so as to be central with regard to this extension, even if it be eccentric with respect to recess 45 and aperture 44. After this adjustment of ring 47 is accomplished, the cement 48 can be poured into recess 45.

Tube extension 14 is shown with the external 85 electrode 16. To this can be connected a long flexible lead 50, that is connected in turn to the conductor 51. This conductor is preferably held against axial movement in sleeve 46. For example, it can be provided with a wedge sleeve 52 that can be urged between the conductor 51 and the constricted opening 53 of the sleeve 46. This sleeve 52 can be glazed into the opening 53 if desired. Apertures 55 can also be provided in 100 the sleeve 46 for ventilating purposes.

In order to assemble the device, the electrode 16 is first connected to lead 50 before sleeve 46 is cemented in place. The tubing 12 can be removed and replaced at will from sleeve 46 even after this sleeve is cemented in place. This is due to the fact that lead 50 is made long enough to permit the lead 50 to extend out of aperture 44 and to be fastened to electrode 16 even when extension 14 is entirely out of that aperture.

105 It often happens that the ceramic character 11 has an uneven thickness. To hold tubing 12 thereover so that this tubing stays parallel to the main support, the supporting clips 56 (Fig. 1) must have a length that varies in accordance 110 with this variation in thickness. I provide a clip structure that can readily be made correct in length to secure this result.

Thus I show a stud 57 (Figs. 5 and 6) having 115 at its upper extremity the spring prongs 58 arranged to encompass the tube 12. This stud has a lower extremity provided with threads 59 for a considerable axial distance. It engages a nut 60 embedded in a recess 61 in the upper face of character 11, in a manner similar to the embedding of screw 30 of Fig. 2. The stud 57 is 120 purposely made long, so that when the tubing is being constructed, it can be cut off at its threaded extremity as by pliers to provide the correct space between the upper surface of character 11 and the tubing 12. It is thus a simple 125 matter to compensate for variations in the thickness of character 11.

In Fig. 7, I show still another form of mounting. In this form, the sleeve 62 is cemented 130 with the recess 45, without the interposition of a ring such as 47. Instead, there is a spring connection clip 63 frictionally engaging the electrode 16 that also serves to hold the extension 14 in place. A hard rubber collar 64 closes the clearance aperture 44. Spring clip 63 is held in place in the bottom of sleeve 62 as by a binding post 65 that passes through the closed bottom of the sleeve 62, and that also effectively serves as a connection means to the flexible insulated lead 66. 135 140 145

I claim:

1. In combination, a luminous tube having an extension, a support for the luminous tube, said support having an aperture into which the extension of the tube can be passed, the end of 140 145 150

the extension having a conductor fastened thereon for leading current into the tube, an insulation sleeve encircling the conductor, and extending a considerable distance beyond the conductor, and means for holding the sleeve on the support, including a resilient ring keying the sleeve into the aperture.

2. In combination, a luminous tube having an extension, a support for the luminous tube, said support having an aperture into which the extension of the tube can be passed, the end of the extension having a conductor fastened thereon for leading current into the tube, an insulation sleeve encircling the conductor, and extending a considerable distance beyond the conductor, means for holding the sleeve on the support, including a resilient ring keying the sleeve into the aperture, and a resilient washer fastened into the aperture and gripping the tube.

3. In combination, a thick insulation support having an aperture and an enlarged recess communicating with the aperture, said recess opening on the reverse side of said support, a flexible washer in the recess, an insulation sleeve in the recess and holding the washer in place in the bottom of the recess, and means keying the sleeve in the recess.

4. In combination, a thick insulation support having an aperture and an enlarged recess communicating with the aperture, said recess opening on the reverse side of said support, a flexible washer in the recess, an insulation sleeve in the recess and holding the washer in place in the bottom of the recess, and a resilient band arranged in a groove in the recess and also engaging in a groove in the periphery of the sleeve.
